DICTATING MACHINE

Heinz Huebner, Fuerth, Germany, assignor to Max
Grundig, Fuerth, Bavaria, Germany

Filed Feb. 26, 1960, Ser. No. 59,535

Term of patent 14 years

(Cl. D26—14)

*FIG. 3.**FIG. 4.*

FIG. 1 is a perspective view showing the top, the front and the right side of a dictating machine embodying the new design, a sliding cover at the top-front corner being open. The wall construction embodied in the right side and comprising the wide, raised, central band, and the two adjacent wall portions on opposite sides of the central band, sloping away from the central band, is continued around the rear end and the left side of the machine casing.

FIG. 2 is a perspective view of the dictating machine as in FIGURE 1 but with the sliding cover closed and with the carrying handle in extended position.

FIG. 3 is a side elevation of the right side of the dictating machine shown in FIGS. 1 and 2.

FIG. 4 is a front elevation of the dictating machine shown in FIGS. 1, 2 and 3 with the sliding cover in closed position and the carrying handle also in closed position as shown in FIGS. 1 and 3.

I claim:

The ornamental design for a dictating machine, as shown and described.
